UNITED STATES PATENT OFFICE.

FRANK R. SINNING, OF RAMSEY, ILLINOIS.

TRACK LINER.

Application filed November 19, 1924. Serial No. 750,769.

To all whom it may concern:

Be it known that I, FRANK R. SINNING, a citizen of the United States, and resident of the city of Ramsey, county of Fayette, and State of Illinois, have invented certain new and useful Improvements in Track Liners, of which the following is a specification, containing a full, clear, and exact description, reference being had to the accompanying drawings, forming a part thereof.

My invention relates to improvements in track liners and has for its primary object a track liner by means of which a great amount of power can be exerted thereby reducing the number of men necessary to line up a track after the same has been laid.

A further object is to construct a track liner in which a lifting movement of the operating lever is employed to operate the device thereby permitting a greater amount of power per man to be applied to the device than is possible where a downward pull is used.

25 In the drawings:

Fig. 1 is an elevation of my device with a rail in section in position and ready to be shifted;

30 Fig. 2 is a top plan view of the same showing the position of the device between the ties and a portion of the rail broken away;

Fig. 3 is a bottom plan view of my device;

35 Fig. 4 is a vertical longitudinal section taken on the line 4—4 of Fig. 2;

Fig. 5 is a top plan view of the socket lever employed; and

Fig. 6 is a vertical cross section of the rail lever taken on the line 6—6 of Fig. 1.

40 In the construction of my device I employ a base 7 which is provided adjacent its forward edge with spaced apart upstanding lugs or ears 8. These ears are perforated so as to permit a bolt or pin 9 to pass therethrough. Located between the ears 8 is the end 10 of the rail lever, which lever is substantially L shaped. The end 10 is provided with an opening through which the pin 9 passes, the opposite end of the lever 45 is also provided with an opening through which the pin 11 passes. The upper surface of the rail lever adjacent the end 10 is flanged as at 12, so as to provide a relatively wide surface which contacts with the base 50 flange of a track rail.

55 Intermediate the ends of the base 7 are

upstanding ears 13 through which a pin 14 extends, the pin 14 also passes through the end 15 of the socket lever, which end is located between the ears. The socket lever is 60 preferably rectangular in cross section and is provided with a bottom 16, and sides 17, these sides are provided with slots 18 through which the pin 11 extends. The pin 11 fits through the rail lever loosely so that 65 it will have a rolling movement when the socket lever is operated and thus relieve friction. The free end of the socket lever is provided with a strengthening flange 19, and adjacent this flange is provided a top 70 20 which is located between the walls 17 so as to form a socket into which a crow bar or similar handle 21 can be inserted.

The pins 9 and 14 are prevented from 75 coming out of the ears 8 and 13 by means of cotter keys 22. The pin 11 also has cotter keys 23 extending therethrough and located on the pin and between each cotter key and the adjacent wall 17 of the socket lever is a washer or disk 24. This washer or disk is 80 for the purpose of preventing the pin from shifting so far as to permit one of the cotter keys to enter one of the slots 18, in which event the roller effect of the pin 11 would be 85 destroyed.

Adjacent the forward end of the base 7 and projecting from its undersurface is a tooth or cleat 25, this cleat extends preferably entirely across the face of the base and in a lateral direction. Parallel to the cleat 25 and some distance to the rear, are spaced apart cleats 26 and to the rear of these cleats is a second set of cleats 27. The cleats 27 are preferably slightly longer than the cleats 25 and 26 so that there will be a slight 90 tendency to have the base inclined downwardly toward the rail. The purpose of these cleats is to prevent the device from 95 sliding.

An important feature of my device is 100 that the surface of the rail lever, which contacts with the rail, is absolutely smooth and being always on an incline, as illustrated in Fig. 1, a slight movement of this lever will raise the rail sufficiently to cause 105 it to clear the ground and permit it to slide readily thus a great deal of vertical movement of the rail during the lining process, is eliminated and therefore the lining of the track is greatly facilitated, because the 110 amount of movement given the rail can be judged to a greater nicety.

2

By constructing my device so that a lift-
ing or an upward movement is used, I gain
quite a lot of power because in this instance,
the operators can make use of their muscu-
5 lar strength whereas in a downward pull
or movement the amount of power exerted
by each individual is limited by his weight,
that being the greatest amount of power he
can possibly exert. It is therefore possible
10 to reduce the number of men on each de-
vice and due to the multiplication of lever-
age this number can be still further re-
duced because fewer devices are necessary.

It will be seen from Fig. 1 that the rail
15 rests on the rail lever only a short distance
from the fulcrum of this lever, which is
the pin 9, while the end to which the power
is applied, which is at the pin 11, is quite
a distance away from this point of contact,
20 this giving me one leverage. This leverage,
however, is increased through the lever sock-
et which has its fulcrum at the pin 14, the
point where the power is exerted being at
the pin 11, which is a relatively short dis-
25 tance from the fulcrum. While the lever
21, which is preferably a crow bar, is many
times the distance between the pins 11 and
14 so that there is an enormous gain of
power between the point where the power
30 is applied and the point where the applied
power does it work. Of course, the mul-
tiplication of power depends on the length
of the lever 21.

In using my device, the commencement
35 of the lifting action is from a point near
the ground so that the operators can utilize
the muscles in the legs, back, shoulders, and
the muscles, thus not only giving the operator
40 greater power but also permitting the
amount of power and consequently the shift-
ing of the track for lining purposes, to be
regulated to a much greater nicety than
where the power is applied by a downward
45 pull.

In addition to my device being useful for
lining tracks it is also possible to use the
device for moving other heavy weights,
such as safes and the like, into position. In
50 this instance, however, the cleats would be
omitted from the bottom of the device and
be replaced by rubber or some similar anti-
slipping surface which would not mar the
floors. This is at present done by means
55 of crow bars and very often the ends of
the crow bars make large dents in the floor.

It will be noted from Figs. 1 and 4 that
the face of the rail lever, with which the

rail contacts, is always inclined downward
toward the fulcrum and by operating the
socket lever the inclination of this face is 60
varied. It will therefore be seen that my
device operates exactly in the same manner
as a crow bar, namely having a smooth sur-
face upon which the rail can slide, and this
smooth surface being capable of having its 65
inclination varied so as to cause the rail to
slide thereon.

Having fully described my invention,
what I claim is:—

1. A track liner comprising a base, a sub-
stantially L shaped rail lever pivoted at
one end to said base and extending upward
at an angle thereto, a socket lever pivoted
to the base to the rear of the rail lever, and
a sliding pivotal connection between the 70
free end of the rail lever and the socket
lever whereby the angle of inclination of
the rail lever to the base may be varied.

2. A track liner comprising a base, a rail
lever pivotally carried thereby, a slotted 80
socket lever pivotally carried by said base,
and a sliding pivotal connection between
said levers whereby the same are sim-
ultaneously raised or lowered when the sock-
et lever is operated.

3. A track liner comprising a base and
a substantially L shaped rail lever pivoted
at one end of face of said base and extend-
ing upward and rearward at an angle there-
to, a slotted socket lever pivotally carried
by the base, a sliding pivotal connection be-
tween said levers for raising and lowering
the free end of said rail lever for varying
its angle of inclination to said base, and
means carried by the opposite face of said
base for holding the same against slipping
when in use.

4. A track liner comprising a base, a rail
engaging lever pivotally secured at its for-
ward end to said base, a socket lever hav-
ing its forward end pivotally secured to
said base and to the rear of the rail engag-
ing lever; the points of pivotal connection
between said rail engaging lever and said
socket lever and the base being immovable,
105 and a sliding pivotal connection between
the free end of the rail engaging lever and
the socket lever whereby the angle of in-
clination of the rail engaging lever with
respect to the base can be varied by the 110
raising of the socket lever.

In testimony whereof, I have signed my
name to this specification.

FRANK R. SINNING.
